UNITED STATES PATENT OFFICE

2,523,063

PEGGED DOOR JAMB SETTING EQUIPMENT

Charles J. Roos, Muskegon, Mich.

Application January 21, 1948, Serial No. 3,576

5 Claims. (Cl. 33—194)

1

This invention relates to improvements in pegged door jamb setting and setting equipment.

An object of the invention is to provide improvements in pegged door jambs and means for setting the same true and square and in line with absolute accuracy.

Another object of the invention is to provide an improved method or means for setting pegged door jambs which insures the absolute centering and squaring of the jambs in jamb openings in a building, whereby the doors when hung in the jambs will be true and free from binding at every point.

A further object of the invention is to provide an improved form of plumb-bob reel and a cooperating marking gauge which will be used in setting a plurality of pegs in a doorway and for measuring the proper positions for cutting off the pegs so that a door jamb when inserted in the doorway will be guided by the pegs to a true and square setting, and in line with absolute accuracy.

A still further object of the invention will be to provide an improved door jamb setting equipment which will be highly efficient in operation, and relatively inexpensive to manufacture and produce.

Other objects will appear as the description proceeds.

In the accompanying drawings which form a part of this application,

Figure 1 is a perspective view of a doorway with portions thereof being removed to show the pegged door jamb centered and in position therein;

Figure 2 is a perspective view of a doorway with the plumb-bob reel and peg marking gauge in position for measuring and marking the pegs where they are to be cut;

Figure 3 is a partial sectional view showing the pegs in the door opening sub-jams or bucks;

Figure 4 is an enlarged detail view partly in section of the plumb-bob reel and peg marking gauge showing the adjustable gauge ends supported thereby;

Figure 5 is a partial sectional view taken on the line 5—5 of Figure 4, and

Figure 6 is a side elevation of the plumb-bob reel with the plumb-bob line wound upon the same.

Like characters of reference are used throughout the following specification and the accompanying drawings to designate corresponding parts.

In carrying out the invention, a series of horizontally disposed pairs of vertically spaced open-

2

ings 1 are bored or otherwise formed in the opposite sides of the sub-jams or bucks 2 of a door opening generally designated by the reference numeral 3, and pegs or dowel pins 4 of any desired material having sharpened ends 5 are driven into said openings, as clearly shown in the drawings.

A pair of transversely spaced nails 6 and 7 are then driven into the face of the upper cross piece 10 connecting the sub-jams or bucks 2, and the improved plumb-bob reel is supported upon said nails 6 and 7. The plumb-bob reel comprises an elongated board or body 9 of a shorter length than the opening between the opposite sub-jams or bucks 2, and supports the pair of arcuate fingers 10 and 11 whose inner curvatures extend towards the ends of said body 9. The fingers extend through the body 9 and above and below the same, and are provided to form a reel 15 upon which the plumb-bob line 12 and attached plumb-bob 13 are wound and supported. An aperture 14 is formed centrally through the body 9 for the reception and passage of the line 12 with the plumb-bob 13 suspended at its lower end.

Cooperating with the plumb-bob reel is a marking gauge comprising an elongated board or body 15 of lesser length than the distance between the side sub-jams or bucks 2, the same being provided with aligned slots 16, 17 and 18, disposed centrally through the body 15, and adjacent the opposite ends thereof.

A centering plate 19 having a pointer line or arrow 20 is secured in the center slot 16 by means of the bolt 21 and wing nut 22, and is normally secured at the center point of the body 15.

End measuring plates 23 and 24 are adjustably supported by the bolts 25 and wing nuts 26 in the end slots 17 and 18, and when properly adjusted and placed directly over the pins 4, permit the marking at 27 on the pins 4 to indicate the points at which they will be cut or sawed off. These measurements are made when the pointer line or arrow 20 aligns with the plumb-bob line 12, thus insuring the exact centering of the door frame 28 in the opening 1 with end contacts being afforded by the ends of the pins 4.

Face plates 29 and 30 will be secured to the edges of the end measuring plates 23 and 24 and will contact the inner edges of the sub-jams or bucks 2 when the marking gauge is in the proper position, thereby further insuring the proper vertical aligning of the door frame 28 when in position. When the door frame 28 is in its correct position between the ends of the pegs

4, as clearly illustrated in Figure 1, it is only necessary to nail the same into secured position.

Thus, it will be seen that the door frame 28 will be exactly centered so that the paneling 31 and door trim 32 will be properly positioned and applied, more especially in narrow hallways.

From the foregoing description it will be seen that there has been devised and provided a highly efficient method of and means for setting pegged door jambs in their proper positions in door 10 openings.

Having thus described my invention, what I claim as new and desire to secure by Letters Patent of the United States is:

1. Apparatus for setting door jambs comprising pairs of pins capable of being cut through, said pins adapted to be inserted in and project from the side sub-jambs of a door opening, a plumb-bob reel supported plumb-bob line and plumb-bob adapted to be supported transversely above said side sub-jambs, and an adjustable measuring gauge the ends of which are cut off square and are supportable on said pins for marking the same for cutting off the projecting portions of the ends of the pins to provide a true and square setting of a door jamb when disposed between the ends of said pins, said gauge having a marking alignable with the plumb-bob line.

2. Apparatus for setting door jambs comprising pairs of pins capable of being cut through, said pins being sharpened at one end to extend into and project from the side sub-jambs of a door opening in vertical spaced relation, a plumb-bob reel supported plumb-bob line and plumb-bob adapted to be supported transversely above said side sub-jambs, an adjustable measuring gauge the ends of which are cut off square and are supported on said pins for marking the pins for cutting off their ends to provide a true and square setting of a door-jamb when disposed between the ends of said pins, and a centering plate with pointer line alignable with the plumb-bob

line adjustably supported by said measuring gauge.

3. The subject matter as claimed in claim 2, said measuring gauge being formed with aligned central and end slots, the centering plate being adjustable longitudinally of the central slot, and end measuring plates constituting said ends of the measuring gauge and supported above and adjustable longitudinally of said end slots.

4. The subject matter as claimed in claim 2, said measuring gauge being formed with aligned longitudinal central and end slots, said centering plate being supported over and adjustable longitudinally of said central slot, and flat horizontally disposed end measuring plates constituting said ends of the measuring gauge supported above and adjustable longitudinally of said end slots.

5. The subject matter as claimed in claim 2, said measuring gauge being formed with aligned longitudinal central and end slots, said centering plate being supported over and adjustable longitudinally of said central slot, flat horizontal end measuring plates constituting said ends of the gauge supported above and adjustable longitudinally of said end slots, and vertical sub-jamb edge engaging aligning plates secured to side edges of said measuring plates and projecting beyond the outer ends of the plates.

CHARLES J. ROOS.
